UNITED STATES PATENT OFFICE.

ELEAZER KEMPSHALL, OF NEW BRITAIN, CONNECTICUT.

SASH-FASTENER.

SPECIFICATION forming part of Letters Patent No. 257,722, dated May 9, 1882.

Application filed March 6, 1882. (No model.)

To all whom it may concern:

Be it known that I, ELEAZER KEMPSHALL, of New Britain, in the county of Hartford and State of Connecticut, have invented certain new and useful Improvements in Sash-Fasteners, of which the following is a specification.

My invention relates to improvements in sash-fasteners of the class which are designed to be inserted through one of the vertical rails 10 of the sash, and in which a cast-metal case is screw-threaded on its periphery and receives a slotted bolt and spring held within the case by a pin which passes through the sides of the case and through the slot in that part of the body of the bolt which is within the case; and the objects of my invention are to make a better and more substantial bolt than those generally found in this class and to produce the same at a small cost. I attain these objects 15 by the mechanism illustrated in the accompanying drawings, in which—

Figure 1 is a side elevation; Fig. 2, an end view. Fig. 3 is a longitudinal section on line $x x$ of Fig. 2, showing the bolt and spring in 20 elevation; and Fig. 4 is a longitudinal section on line $y y$ of Fig. 2.

I make the case A substantially of cylindrical form, of cast metal, all in one piece, and preferably with a screw-thread on its periphery. I also form a slightly-projecting flange, 30 a' , at the large end, which, for convenience of description, I will term the "outer end."

The case A is cast hollow to receive the bolt B and spring a , and the orifice in its outer end, 35 and also that end of the bolt, is in the form of a circle truncated or slabbed off upon two opposite sides, as clearly shown in Fig. 2. The orifice at the inner end of the case and the portion of the bolt which fits therein is of less size 40 and of a circular form.

The stem of the bolt is straight and of uniform size from the shoulder b , against which one end of the spring a abuts, to a point wholly outside of the case, and no part of the inner 45 end of the bolt is of any larger size.

The extreme outer end of the bolt is provided with a knob, f , for use as an operating handle.

The body of the bolt has a longitudinal slot, e , through it at a point which is wholly within 50 the case.

The bolt and spring are inserted from the outer end and secured therein by the transverse pin d , which passes through the sides of the case and the slot in the bolt. Said pin 55 limits the movement of the bolt in both directions.

I make the case of a larger diameter than ordinary bolts of this class and shorter than the width of ordinary sash-rails. 60

In order to put the device in place, a hole is bored partly through the rail C, Fig. 4, of size proper to receive the case A, and the remainder of the way a smaller hole is bored, large enough to let pass freely the small end of the bolt, as 65 shown in said Fig. 4. The device is then screwed in place by applying a wrench to the flattened sides of the outer end of the bolt.

I am aware of the Letters Patent to M. L. Kingsley, April 9, 1878, E. B. Beach, September 21, 1875, and to Franklin Babcock, September 29, 1868, and I hereby disclaim all that 70 is therein shown and described.

I claim as my invention—

A sash-fastener consisting of the solid cylindrical case having a screw-threaded periphery and the flattened orifice at its outer end, the spring-actuated bolt projecting from both ends of said case and having its outer end of a flattened form corresponding to that of the flattened orifice in the case, and having also the longitudinal slot through which the pin passes, substantially as described, and for the purpose specified. 75 80

ELEAZER KEMPSHALL.
